UNITED STATES PATENT OFFICE.

THOMAS EARL DAUGHTON, OF DOOLEY, VIRGINIA.

SODA-DISPENSING DEVICE.

Application filed August 24, 1922. Serial No. 584,065.

To all whom it may concern:

Be it known that I, THOMAS E. DAUGHTON, a citizen of the United States, residing at Dooley, in the county of Wise and State 5 of Virginia, have invented certain new and useful Improvements in Soda-Dispensing Devices, of which the following is a specification.

This invention relates to new and useful 10 improvements in liquid dispensing devices, the primary object of the invention being to provide a device including an automatically operable valve and means for operating the same arranged so that when a receptacle is positioned to receive liquid from the dispensing device, the valve will be automatically opened to permit the flow of 15 liquid from the device into the receptacle.

Another important object of the invention 20 resides in the provision of a device of the above description and which includes means for simultaneously operating a pair of conduits so that the material travelling through both conduits will be discharged 25 simultaneously and from the same nozzle, this arrangement being found advantageous in dispensing carbonated water at soda fountains.

A further object of the invention resides 30 in the provision of a button arranged directly under the dispensing nozzle for actuating valve means associated with the nozzle when a receptacle is positioned upon the button to receive liquid from the 35 nozzle.

A still further object of the invention resides in the provision of a simple and durable valve operating means which is highly efficient for the purposes designed in practice. 40

Other objects and advantages of the invention will become apparent during the course of the following description.

In the accompanying drawings forming a 45 part of the description and wherein like numerals are employed to designate like parts throughout the several views,

Figure 1 is a fragmentary perspective view of a soda fountain equipped with the 50 invention,

Figure 2 is a transverse section through the same showing the application of the invention,

Figure 3 is an enlarged longitudinal section of a modified form of valve chamber,

Figure 4 is a detail perspective view of

various parts of the valve operating mechanism, and

Figure 5 is an enlarged detail perspective view of the head of one of the valves. 60

Referring more particularly to the drawings and wherein for the purpose of illustration is shown the preferred embodiment of the invention, the numeral 6 designates a support for glasses, receptacles and the 65 like, and which in the present instance assumes the form of a soda water dispensing fountain. This support 6 is equipped with one or more vertical openings 7 in which

operates a part of a valve mechanism which 70 will be presently described. For every opening in the support a dispensing pipe or nozzle 8 is provided and in the present instance, the discharge end of each nozzle points downwardly towards the support 6 75

and is preferably arranged vertically above its respective opening 7. The end of the dispensing pipe or nozzle 8 which enters the fountain is connected to a vertical pipe 9, the lower end of which is connected through 80

an L-shaped valve casing 10 by means of a sleeve union 11. The end of the horizontal leg of the casing is connected to a pipe 12 which in turn leads from a source of supply 13. 85

The horizontal leg of the casing is provided with a vertically disposed partition 14 which is equipped with a tapered opening 15 forming a valve seat therein. A valve stem 16 is slidably mounted in the 90 horizontal leg of the valve casing and extends through the opening in the partition 14 and also through a packing associated with the wall of the vertical leg of the valve casing so that the outer end of the stem is 95 disposed exteriorly of the valve casing. The inner end of the valve stem is provided with a valve head 17, the inner end of which is tapered to snugly fit its seat in the partition 14, while the outer end of the valve 100 head is tapered into a point so that it offers as little resistance as possible to the liquid or air flowing through the valve casing to be dispensed at the nozzle 8.

A link 18 is pivotally connected at one 105 end to the outer end of the valve stem 16 as shown, and at its opposite end to a vertical arm 19 of a bell crank lever which is pivotally connected as at 20 to a bracket 21 depending from the support 6. The horizontal arm 22 of the bell crank is pivotally connected at its free end to the lower end 110

2
of a stem depending from a receptacle platform 24 arranged in its opening 7 of the support 6. The stem 23 extends through the bottom of a cup-shaped casing 25 which 5 is arranged in each opening 7 in the support so that the upper end of the cup-shaped casing is arranged flush with the upper surface of the support. The platform 24 secured to the upper end of the 10 stem has its lower portion normally disposed within the cup-shaped casing, while the upper surface or top of the platform is normally disposed thereabove by means of a coil spring 26 placed on the platform stem 15 23 within the casing 25 so that one end of the spring abuts the bottom of the casing 25 and its opposite end engages the bottom of the platform 24 to normally urge the same upwardly to the position hereinbefore 20 mentioned.

The spring 26 is of a very light nature, the tension of which is such that the spring can be readily compressed by the weight of an ordinary soda water glass positioned 25 upon the platform 24. The connections between the platform and valve are also made very light so that the valve may be opened simply by the weight of a soda glass resting on the platform. As the valve mechanism and platform structure for each dispensing nozzle is the same, the description given for one will suffice for all.

The device hereinbefore described will serve for dispensing liquids under pressure 35 flowing into the valve casing, but in order to dispense carbonated water with as simple arrangement as possible, and with the valve mechanism employed herein, a valve casing 26' as shown in Fig. 3 is provided which is 40 of L-shaped configuration as in Fig. 2 and the vertical leg of which is provided with a vertical partition 27, thereby dividing the valve casing into a pair of separate and distinct chambers or compartments 28 and 29. The chamber 29 has its top closed as seen, and into this top is threaded the lower end 45 of a gas pipe 30 which is smaller in diameter than the pipe 9 and dispensing nozzle 8 and is therefore conveniently extended 50 through pipe 9 and nozzle 8 as shown. The horizontal leg of the L-shaped valve casing 26' is also divided longitudinally by a vertical partition to separate the same into a pair of distinct conduits to which are connected a pair of distinct conduits or pipes 55 31 and 32, the latter in the present instance being connected to chamber 29 and adapted to pass gas such as used in carbonating water through the pipe 30. The other conduit or pipe 31 is adapted to pass water into chamber 28. Each of the compartments 28 and 29 is provided with a vertical partition, in each of which is provided a valve seat, the same as that shown in Fig. 2 so that a 60 65 separate valve may be used for controlling

the entrance of a medium into the chambers 28 and 29. The stems of these valves are designated by the numeral 33 and each is pivotally connected to the link 18, which in turn is pivotally connected to the vertical arm 19 of a bell crank, as in the form of invention disclosed in Fig. 2. The rest of the valve operating mechanism is the same for this modification as for the form of invention shown in Fig. 2 and from the description thus far, it will be seen that whenever a glass is positioned upon the platform 24, that the spring 26 will be compressed to swing the horizontal arm 22 of the bell crank downwardly and the vertical arm 19 70 75 inwardly toward the valve casing to slide both valve stems 33 inwardly thereby permitting both water and gas to flow into their respective chambers in the valve casing and thence through pipes 9 and 30 to be 80 85 combined adjacent the dispensing nozzle 8 to make carbonated water discharge from the nozzle into the receptacle resting on the platform.

In order that two different kinds of 90 liquids may be dispensed from the same nozzle 8 and separate from each other, the same valve arrangement as shown in Fig. 3 may be employed, but instead of having the link 18 control both valve stems 33, a 95 separate link and lever connection as shown in Figure 1 is made between each valve stem 33 and each operating button. A button 24 may be used for controlling one of the valves while a second button 25 elongated 100 in configuration will be employed for operating the other valve so that a receptacle or glass can be placed upon either of the buttons 24 or 25 so that either one of two kinds of liquids can be dispensed separately. 105

The foregoing description and accompanying drawings have reference to what might be considered the approved or preferred form of my invention. I desire it to be understood that I may make such changes 110 in the construction, combination and arrangement of parts, materials, dimensions, et cetera, as may prove expedient and fall within the scope of the appended claims.

Having thus fully described my invention 115 what I claim is:—

1. In a liquid dispensing apparatus, a dispensing conduit including a valve casing having a vertical partition therein equipped with a valve seat, a horizontally movable valve associated with the seat and having its end projecting exteriorly of the valve casing, a link pivotally connected to the outer end of the valve stem, a bell crank having a vertical arm pivotally connected to the outer end of the valve stem, and a 120 125 depressible platform having pivotal connection with the arm of the bell crank normally arranged in a horizontal plane.

2. In a liquid dispensing apparatus com- 130

- prising a dispensing conduit including a valve seat, a dispensing spout, a support arranged below the same and having an opening therein directly below the spout,
- 5 a bracket depending from the support, a bell crank lever pivotally connected to said support, a vertically movable receptacle platform pivotally connected to one arm of the bell crank and mounted in said opening,
- 10 a link pivoted to the other arm of the bell crank, a valve stem pivotally connected to said link and being slidably mounted in said dispensing conduit and having a valve head for cooperation with said valve seat.
- 15 3. A liquid dispensing apparatus comprising a dispensing conduit, a valve casing arranged therein and divided into a pair of separate and distinct chambers, each com-
- municating with said dispensing conduit, a separate supply pipe communicating with 20 each chamber for directing material thereto, a valve associated with each chamber for regulating the flow of material there-through, a valve stem for each valve slidably mounted in said valve casing, a link 25 pivotally connected to both of said valve stems, and means connected to said link for operating the same whereby the two valves are simultaneously operated to control the flow of material through the two chambers. 30

In testimony whereof I affix my signature in presence of two witnesses.

TOM EARL DAUGHTON.
